Inventor
Leverett W. Tiffany
By his Attorneys
Duell, Washburn & Duell

UNITED STATES PATENT OFFICE.

LEVERETT W. TIFFANY, OF WINSTED, CONNECTICUT.

LEVEL ATTACHMENT.

Application filed June 27, 1923. Serial No. 647,976.

To all whom it may concern:

Be it known that I, LEVERETT W. TIFFANY, a citizen of the United States, residing at Winsted, in the county of Fairfield and State 5 of Connecticut, have invented certain new and useful Improvements in Level Attachments, of which the following is a full, clear, and exact description, such as will enable others skilled in the art to which it appertains to make and use the same.

This invention relates to an instrument, such as a level, and aims to provide a device of this character presenting certain improved constructions over articles of this 15 nature, as heretofore designed.

It is an object of the present invention to provide a device of the type stated, with which certain mechanism is associated, whereby the degree of inclination of a surface may be accurately and quickly ascertained.

A further object of this invention is that of providing mechanism which may be in the nature of an attachment to a level or similar 25 instrument, and which will be capable of being manufactured at a nominal cost.

A still further object of this invention is that of constructing an attachment capable of being associated with an instrument 30 such as a level without necessitating a modification of construction on the part of the latter.

Another object of the invention is that of furnishing a level attachment, the parts of 35 which may readily be assembled or detached from each other by an inexperienced person and without the employment of any tools.

Still another object of the invention is that of providing an attachment preferably 40 for use with a level, which attachment when in use will present an indicator capable of being quickly read, and which when not in use will in nowise interfere with the customary usage of the level for the ordinary 45 purposes in connection with which the latter is employed.

Other objects of the invention will in part be obvious and will in part appear herein-after.

For a fuller understanding of the nature 50 and objects of the invention reference should be had to the following detailed description taken in connection with the accompanying drawing, in which:

Fig. 1 is a side elevation of a conventional

form of level and showing the mechanism of this invention in use thereon,

Fig. 2 is a fragmentary sectional side view of one end of the level, this view being taken along the lines 2—2 and in the direction of 60 the arrows indicated at Fig. 3, and

Fig. 3 is an end view of the device as shown in Fig. 1.

In these several views it will be noted that the numeral 5 indicates the body of a level 65 with which there is associated as at 8 any desirable type of level tube 6. It is to be here understood, however, that although the present invention is particularly designed for use in connection with a level that the 70 attachment may be utilized to advantage in numerous different associations.

Referring to the construction of the device, it will be noted that in the present instance the mechanism has been shown in 75 the nature of an attachment to the level, and thus the numeral 7 indicates a plate which forms the base of the attachment and is secured to one end of the level body 5. To provide means acting as a level supporting leg and serving to support the level body in a plane inclined with respect to the surface upon which it rests, and to also provide angle indicating means, serving to register the degree of this inclination, it will be 80 noted that in the present instance a plate 9 is employed. This plate is slidably mounted upon the base of the attachment, and is retained in applied position with respect thereto by any suitable means, such as for example by utilizing a headed pin 10 which has its stem projecting into the level body, its outer end extending beyond the base of the attachment and through a slot 11 in the body of the plate. A screw 12 is employed 85 for the same purpose, and likewise extends into the body of the level, through an opening in the base and through a slot 13 in the plate 9, and in order to provide means serving to engage the thread of this screw and to 90 permit of the same being rotated with respect to the body of the level, it is preferred that the latter be tapped to receive a nut 14 for the accommodation of the stem of the screw. The head of the screw is knurled as at 15, 95 and a spring washer 16 may encircle the stem of this member and be interposed between the head of the same and the plate 9.

It is obvious that by releasing the pressure upon the washer 16, the plate may be 110

freely moved longitudinally of the base, and after these elements are brought to a desired position with respect to each other, a subsequent tensioning of the washer, by means of the screw, will cause the former to bear against the plate and exert sufficient pressure to prevent any movement of the parts. If it is desired to completely remove the plate from the base, this may readily be accomplished by simply removing the screw 12 and subsequently swinging the plate to extend in a line substantially at right angles to the base, at which point by virtue of the fact that certain of the edges of the head of the pin 10 have been cut away, as is indicated at 17, the plate may be entirely removed from the base, it being noted in this connection that the flattened portion 17 of the pin head is arranged in such a manner that the space between the edges of the same is less than the distance between the longitudinal edges of the slot 11.

The lower edge of the plate 9 may be turned as indicated at 18 to provide a foot portion which will bear against a supporting surface as has been indicated in Fig. 1, and if desired the upper edge of this plate may be bent outwardly to provide a manipulating portion 19 by means of which the said plate may be moved with respect to the base of the attachment. In order to provide an indicator for the device which will register the amount of movement of the plate with respect to the base, the latter may present a series of graduations 21 and a portion of the plate 9 may be cut out or notched as at 20, and thus it will be understood as has been clearly brought out in Fig. 3, that the greater the movement of the parts aforementioned the greater will be the number of graduations 19 which will be exposed.

In applying the attachment to a level it will be understood that the base of the former is secured to the body of the latter in any desirable manner, such as for example by the means aforescribed, and the plate 9 may be likewise secured to the base. Normally the lower end of the plate may align with, or be raised beyond the lower edge of the level body, so that this member may be utilized in a conventional manner. Assuming that it is desired to employ the attachment to measure the degree of inclination, for example, of the surface indicated in Fig. 1, the level body is rested upon this surface and the plate of the attachment is moved to the position shown in the figure aforementioned, and the parts are adjusted

until the bubble, or other indicator employed in the level, reaches its proper position. By means of the head 15 of the screw 12, the latter may now be tightened and by ascertaining the reading of the scale provided by the graduations 21 and the edge of the notch 20, the exact degree of inclination 60 65 70 75 80 85 90 95 100 105 110 may be had.

Thus, it will be obvious that all the objects of this invention are accomplished, and it is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A level attachment, including a base, a plate beyond and movable over the outer face of said base, the upper corner of said plate being formed with a notch, said base being formed with a scale upon its outer face and adjacent its side edge, the graduations of said scale being visible within said notch, said plate being formed with a slot, a headed screw connected with said base and having its shank extending through said slot, and a split-washer encircling said shank and engaged by the inner edge of the screw head, the inner edge of said washer bearing against the outer face of said plate to retain the parts in applied position.

2. A level attachment, including a base, a plate beyond the same and movable thereover, said plate being formed with a pair of longitudinally-extending slots arranged parallel to each other, a headed screw associated with said base and having its shank 100 extending through one of said slots whereby said parts may be prevented from moving relatively to each other, a headed member also associated with said base and having its shank extending through the second of 105 said plate slots, its head being disposed transversely of the direction of said slot whereby after detachment of said screw said plate may be swung to have that slot extend parallel to said head to permit of a detachment of said parts, and means for registering the relative amount of displacement of said base and plate.

In testimony whereof I affix my signature.

LEVERETT W. TIFFANY.
